CLAIM

The ornamental design for a glove for protection, as shown and described.

DESCRIPTION

1.-2. Glove for protection

1.1 is a front view of a glove for protection showing my new design;

1.2 is a side view thereof;

1.3 is a rear view thereof;

1.4 is an opposite side view thereof;

2.1 is a front view of a second embodiment of a glove for protection showing my new design;

2.2 is a side view thereof;

2.3 is a rear view thereof; and

2.4 is another side view thereof.

The broken lines showing a glove are for the purpose of illustrating portions of the article and form no part of the claim.
